UNITED STATES PATENT OFFICE.

GEORGE W. FROST AND ERNEST O. ZACHARIAS, OF SPRINGFIELD, ILLINOIS, ASSIGNORS
TO SHANKLIN MANUFACTURING CO., OF SPRINGFIELD, ILLINOIS.

ACETYLENE LAMP.

Application filed March 21, 1924. Serial No. 700,798.

To all whom it may concern:

Be it known that we, GEORGE W. FROST and ERNEST O. ZACHARIAS, citizens of the United States, residing at Springfield, in the county of Sangamon and State of Illinois, have invented a new and useful Acetylene Lamp, of which the following is a specification.

The invention relates to improvements in acetylene lamps of the type commonly used by miners, said lamps comprising a box containing water, applied on the carbide in due time and quantity to generate acetylene gas regularly as needed; a burner tube receiving gas from the carbide box, a burner tip at the outer end of the burner tube; a reflector detachably connected with the reservoir, an igniter mounted in the reflector in operative relation to the burner tip, and a hook fixed on the reservoir and used to connect the lamp with the miner's cap.

The objects of the present invention are; to provide improved means for detachably connecting the reflector with the burner tube and the reservoir, to prevent rotation of the reflector on the burner tube and thereby maintain proper position of the igniter relative to the burner tip; to provide a resilient ring detachably connected with the reservoir and carrying arms co-acting with the hook on the reservoir to prevent swinging of the lamp on the miner's cap; to provide a collar of improved construction between the reflector and the reservoir, contributing to the general symmetry of the lamp; and to provide improved means preventing leakage of gas around the detachable resilient ring carrying the braces or arms.

We attain these objects by the mechanism illustrated in the accompanying drawing, in which—Figure 1 is a side elevation of a miner's lamp embodying our invention; Fig. 2 is a front view of the reflector, the burner tip and the igniter in operative relation to each other. Fig. 3 is a vertical section through the reflector, the burner tube, and the collar; and through a fragment of the upper part of the reservoir, taken on the line 3—3 of Fig. 2; Fig. 4 is a horizontal transverse section through the lamp taken on the line 4—4 of Fig. 1; Fig. 5 is a rear view of the detached collar; Fig.

6 is a front view of the detached collar; Fig. 7 is a vertical section through the collar taken on the line 7—7 of Fig. 5; and Fig. 8 is an enlarged vertical section through the lower rim of the housing, the resilient ring in the rim, and the gasket and through a fragment of the carbide box.

Similar numerals refer to similar parts throughout all the views.

The main structure of the lamp comprises a carbide box 12 having a screw-threaded neck 17; a water-reservoir 13 having a circular flared rim-member 14 a circumfential bead 15; and a screw-threaded member 16 engaging on the neck 17 to unite the carbide box and the reservoir.

The reservoir has the usual water-tight floor or diaphragm, not shown. The burner tube 18 extends downwardly through the diaphragm, and conducts gas from the carbide box to the burner tip 19,

The igniter comprises a standard 20 firmly attached to the reflector and supporting the usual rotative sparking-wheel 21. In Fig. 2 the igniter is shown in the preferred position relative to the burner; the present invention includes means whereby the assembling of the reflector and the collar on the reservoir will automatically result in proper positioning of the igniter relative to the burner tip, thereby expediting proper assembling of the parts and avoiding great annoyance and possible injury to the user, which might result from misplacement of the igniter.

The collar 24, shown in detail in Figs. 5, 6, and 7 serves to prevent rotation of the reflector on the burner tube and to hold the reflector plumb, and also serves to determine the position of the igniter relative to the burner tip. The collar is a circular box-like structure made from a sheet metal disk pressed to form a circular rim 25 having a radial notch 26 to receive the protuberance 23 on the back of the reflector; a central member 27, concave on its inner face to conform to the curvature of the back of the reflector and convex on its outer face, and having a hole 28 to receive the burner tube, a flat outer face 29 having an integral protuberance 30, which bears on the member 16 to give rigidity to the structure; and an integral transverse member 31 convex on its

inner face and concave on its outer face to receive the circular bead 15 on the reservoir

13. The bead 15 on the reservoir 13 engages in the concavity 31 to prevent rotation of the collar on the burner tube. To assemble the parts 22 and 24 in proper position on the reservoir 13 the collar 24 will be placed on the tube 18 in such a position that the bead 15 will be in the concavity 31; 10 the reflector 22 will be placed on the tube with the back of the reflector in contact with the concave face 27 of the collar and the protuberance 30 in contact with the member 16 of the reservoir, and when the 15 parts are thus assembled the protuberance 23 on the back of the reflector will be in the notch 26 in the collar; the nut 32 will be screwed on the pipe 18 to secure the assembled parts; and the burner tip 19 will 20 be pressed into the end of the tube.

A hook 33 soldered on the reservoir 13 is used to support the lamp on the miner's cap.

Braces soldered on the reservoir and extending outwardly therefrom and having terminals engaging in holes in a plate on the cap have been used to prevent swinging of the lamp which is annoying to the user. The lamps are subject to severe service and the arms or braces are often broken and detached from the lamp and in that case it is necessary to take the lamp to a shop for repair. To overcome this objection we provide a resilient wire ring 34 having integral outwardly extending arms, 25 or braces 35 having terminals 36 adapted to engage the plate commonly used on miner's caps to prevent swinging of the lamp.

The metal of the rim-member 14 is spun 40 downward and inward to form a circular channel 37 containing the ring 34 which is loose in the channel. The arms 35 extend outwardly through notches 38 in the rim 14. Upon pressing the arms towards each 45 other the ring will be contracted sufficiently to permit the ring to be inserted in, or withdrawn from, the channel 37.

An annular rubber gasket 39 at the junction 50 of the carbide box 12 and the reservoir 13 (Fig. 8) is in gas-tight contact with the outer face of the carbide box and the inner face of the member 14 so that gas cannot leak between the members 12 and 14 nor through the notches 38. The construction 55 described avoids the necessity for soldering the braces on the reservoir, thereby reducing the cost of manufacture, and furthermore admits of easy replacement of broken braces without the delay and expense of taking them to the repair shop.

Having fully described our invention

what we claim as new and desire to secure by Letters Patent is.

1. In an acetylene lamp, the combination 65 of a reservoir having a circumferential bead; a burner tube extending outwardly through the wall of the reservoir; a collar having a concavity to receive the bead on the reservoir, also having a radial notch; a concavo-convex reflector having on its convex face a protuberance engaging in the radial notch of the collar to prevent rotation of the reflector relative to the collar; and a sparking wheel supported in the reflector 70 and rotatable in a plane radial to the reflector 75 and common to the notch in the collar and the protuberance on the convex face of the reflector; and a nut on the burner tube securing the reflector and the collar in fixed relation to each other and in fixed relation 80 to the reservoir.

2. In an acetylene lamp, the combination 85 of a reservoir; a burner tube extending outwardly through the wall of the reservoir; a burner tip in the burner tube; a reflector in operative relation to the burner tube; a sparking wheel rotative on a support in the reflector; a protuberance on the convex face of the reflector and in the plane of rotation 90 of the sparking wheel; and a collar in fixed relation to the reservoir and having a notch to receive the protuberance on the reflector to determine the position of the igniter relative to the burner tip.

3. In an acetylene lamp, the combination 95 of a reservoir having a rim-member having a circular channel, and radial notches; a hook fixed on the reservoir; a removable resilient ring free in said circular channel in the rim; and arms integral with said ring 100 and extending outwardly through the notches in said rim, in co-operative relation to the hook on the reservoir.

4. In an acetylene lamp the combination 105 of a reservoir having a rim-member having a circular channel and radial notches; and a resilient ring loose in the channel of said rim member and having integral arms extending outwardly through the notches in the rim member and compressible to contract 110 said resilient ring to permit insertion of said ring in and its withdrawal from said channel in the rim member.

In witness whereof we have hereunto signed our names at Springfield, Illinois, 115 this 13th day of March, 1924.

GEORGE W. FROST.
ERNEST O. ZACHARIAS.
